CLAIM

The ornamental design for a metal detector, as shown and described.

DESCRIPTION

FIG. 1 is a front elevational view of the metal detector showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a front, right side perspective view thereof.
The broken lines illustrate portions of the metal detector that form no part of the claimed design.
